UNITED STATES PATENT OFFICE.

MARION T. BROADY, OF BARTLE, INDIANA.

CORN-PLANTER.

SPECIFICATION forming part of Letters Patent No. 367,781, dated August 9, 1887.

Application filed May 13, 1887. Serial No. 238,659. (No model.)

To all whom it may concern:

Be it known that I, MARION T. BROADY, a citizen of the United States, residing at Bartle, in the county of Washington, State of Indiana, have invented certain new and useful Improvements in Corn-Planters, of which the following is a specification, reference being had therein to the accompanying drawing.

This invention has relation to corn-planters, and has for its object, among other things, the provision of a planter that can be manufactured at a minimum cost, that is light and durable, and the dropping mechanism of which can be thrown into and out of operation.

15 Other objects and advantages of the invention will hereinafter appear, and the novel features thereof will be particularly pointed out in the claims.

Referring to the drawing, which represents a 20 corn-planter constructed in accordance with my invention, A represents the frame-work of the planter, which is of ordinary construction, and provided with the longitudinal parallel bars A', connected at their forward end to a 25 transverse bar, A², and to the front of the frame is connected the usual draft-pole, A³. Journaled in bearings A⁶ is the axle A⁴, adapted to rotate therein by means of the ground-wheels A⁶, mounted thereon.

30 Mounted upon the axle and rigid therewith is a gear, B, and at each side thereof are mounted sliding collars B', connected by means of curved levers B², pivoted to each other above the gear, as at B³, and connected at their 35 upper ends by a chain, B⁴, an arch, B⁵, mounted on the bars A', being also pivoted at B³ to said levers, and serving to maintain the same in a vertical position above the gear B. The lower ends of the levers are bifurcated or yoke shape, 40 and are mounted in grooves formed in the collars B'. Extending laterally from the collars B' are rods B⁶, at the outer ends of which are secured collars or clamps B⁷, mounted in 45 grooves in sleeves B⁸, mounted upon the axle between the frame-work and the wheels, said collar being formed with serrations or teeth at both sides, and adapted by the levers to be thrown into and out of contact with similar teeth formed on the inner side of the hub, as at B⁹, of the wheel, and a plate, B¹⁰, fixed to the 50 side of the frame. A spring, B¹¹, mounted be-

tween the levers B², serves to normally maintain the same spread, and consequently the toothed sleeve B⁸ in mesh with the hub B⁹, and thus the planter being drawn along causes 55 the gear B to rotate.

C represents the driver's seat, which is mounted at the rear end of the frame A, and the chain B⁴ of the levers B² is within easy access thereto, so that by pressure of the foot 60 upon said chain the levers will be inwardly drawn and the sleeve B⁸ will be thrown out of mesh with the hub B⁹, whereby the rotation of the gear B and the operation of the planter, which is driven thereby, as hereinafter described, ceases.

In front of the gear B, in suitable bearings, is a transverse shaft, D, formed with cranks D' at its ends, and provided at its center with a gear, D², adapted to mesh with the gear B, 70 and be driven thereby.

At the front of the frame-work, and at each side thereof, is arranged suitable seed-dropping mechanism, and in this instance it comprises a hopper, E, the bottom of which is 75 formed with a longitudinally-slotted plate, E', having a perforated slide, E², connected with and oscillated by the crank-shaft D by means of a pitman, E³, and registering with a seed spout or tube, E⁴, projecting down and between and in rear of a bifurcated shoe or runner, E⁵, provided with a rear brace, E⁶.

Sight-posts F, mounted at each side of the frame-work, serve as a means by which the driver may maintain the planter in a straight 85 line with similar posts set in the land at suitable points.

A marking-bar, G, having a marker, G', at its end, and pivotally connected to the frame-work, as at G², is provided at the front of the frame-work, and may operate at either side of the machine, it being supported, when lowered to position, by means of brackets G³, secured to the ends of the frame and projecting therefrom. Both of the sides of the marker G' 95 terminate in bifurcations, whereby a more visible mark is made than would be by the edge of the marker itself.

For the purpose of providing means whereby the front of the planter may be elevated, so as 100 to allow the runners and seed-dropping mechanism to pass over obstructions, and thereby

preventing straining and breaking said mechanism, I have provided a tilting frame, II, pivoted as at II', projecting beyond the front of the machine, and provided with a caster-wheel, II², journaled therein. A light frame, I, mounted upon a shaft, I', secured to the bars A', the forward end resting under the rear end of the frame II, serves as a means for raising said rear end of the frame II, and consequently the front end of the frame-work of the planter. After being connected to the rod I' the frame I is downwardly, rearwardly, and upwardly bent, as at I², so as to pass in rear of the gear B, and within easy access to the foot of the operator, the operation of raising the planter being to press downwardly upon the rear end of the frame I, which will perform the function and operation heretofore described.

Having described my invention and its operation, what I claim is—

1. In a corn-planter, and in combination with the axle and ground-wheels thereof, the hubs of the latter provided with teeth, a gear mounted on said axle, collars and sleeves mounted at each side thereof, the latter having teeth and levers crossing and pivoted to each other and mounted on the collars, and rods connecting said collars to said sleeves, substantially as specified.

2. The combination of the frame-work and axle of a corn-planter, the latter provided with a gear at its center, and with ground-wheels

having teeth at their inner ends, toothed sleeves mounted on the axle between the hub and frame-work, and levers crossing and pivoted to each other and connected by a chain for throwing the sleeves into and out of connection with said hub, with a crank-shaft having a gear, and seed-dropping mechanism connected with said shaft, substantially as specified.

3. The hopper E, having the slotted bottom E', the perforated slide E², the pitman E³, and mechanism for operating the same, in combination with the bifurcated runner E⁴, the brace E⁵, depending from the frame and connected with each side of the runner, and the seed-tube E⁶, substantially as specified.

4. In a corn-planter, the combination of the frame-work A, the tilting frame II, pivoted, as at II', thereto, and having the caster II², with the frame or lever I and rod I', substantially as specified.

5. The frame A, in combination with the axle A', having the wheels A² and gear B, the collars B', sleeves B², the rods B³, the plates B⁴, the levers B⁵, connected as at B³ and B⁴, substantially as specified.

In testimony whereof I affix my signature in presence of two witnesses.

MARION T. BROADY.
